LOCK FOR LUGGAGE CASES AND THE LIKE

Erwin Kalla, West Pittsburg, Pa., assignor to Reliable Luggage, Inc., West Pittsburg, Pa., a corporation of Pennsylvania

Application March 15, 1957, Serial No. 45,276

Term of patent 14 years

(Cl. D50—7)

Fig. 1.

Fig. 2.

Fig. 1 is a plan view of a lock for luggage cases and the like, showing my new design; and

Fig. 2 is a side elevation thereof taken from the right of Fig. 1.

I claim:

The ornamental design for a lock for luggage cases and the like, as shown.
